(Cl. D59—8)

To all whom it may concern:

Be it known that I, Meyer Cohen, a citizen of the United States, residing at Flushing, in the county of Queens and State of New York, have invented a new, original, and ornamental Design for a Mailing Envelope, of which the following is a specification, reference being had to the accompanying drawing, forming part thereof.

Figure 1 is an inside plan view of an envelope in an unfolded position;

Figure 2 is a rear view of the envelope folded but with the flap open; and

Figure 3 is an edge elevational view of the disclosure in Figure 2, showing my new design.

The front of the envelope is plain and the essential feature resides in the ornamentation on the interior of the envelope.

I claim:

The ornamental design for a mailing envelope, as shown and described.

MEYER COHEN.
